10 Claims. (Cl. 175—213)

This invention relates to a device for supplying fluid to a drill tool at one end of a string of hollow drilling elements for flushing, cooling or operating said drilling tool or for other purposes.

In carrying out various forms of deep hole drilling, such as rotary drilling, percussion drilling or down the hole drilling or the like it is common practice to employ a string of drilling elements which may be screwed together or otherwise connected in a manner to make possible successive addition of further drilling elements to the string of drilling elements before the uppermost drilling element vanishes into the ground.

At the leading end of the string a drilling tool or drill bit is provided which, for example, may consist of a pressure fluid driven percussive down the hole drill or a diamond bit or a percussion bit with hard metal inserts or of a roller bit or the like. The type of drilling tool and drill rods or elements used depends upon the kind of drilling carried out, for example rotary drilling, turbine drilling, calyx drilling, diamond drilling or percussive drilling. Common to these various types of drilling operation is that a flushing medium is employed for rinsing or cooling the drilling implements or bits and for removing and carrying away the drill cuttings, debris and the like. Said flushing medium may be compressed air or pressure water or a combination of both, as well as other compositions in order to bring about the desired flushing and/or cooling. In down the hole drilling pressure fluid for operating the down the hole drill must also be supplied to said drill through the string of drilling elements.

In carrying out conventional deep hole drilling, for example rotary drilling, the flushing medium is admitted into a hollow rotating drill pipe or rod by means of a swivel coupling which is supplied with flushing medium from a suitable source. Usually the swivel coupling is located at the top of the uppermost drill pipe or rod of the string. When a further drilling element is to be added to the string, the drilling operation has to be interrupted in order to make possible removal of the swivel coupling and transfer of said coupling to the upper end of the next drilling element which is to be added to the string of drilling elements. A serious draw-back of such interruption of the drilling operation and of the flushing is that a part of the drill cuttings or slurry may settle at the bottom of the bore hole and may cause plugging of the drilling implement. This means that the drill bit becomes so stuffed with debris as to necessitate retraction of the entire drill string from the bore hole in order to clean the bit, the core tube or other working implement. Even if no plugging occurs the transfer of the swivel coupling from one drilling element to another requires considerable time during which drilling has to be interrupted and such stops reduce the effective drilling time.

It is a primary object of the invention to provide a device for supplying fluid to a drilling tool at one end of a drill string or drill rod making possible the connection of a further drilling element to said drill string while drilling is in progress and without interruption of the fluid supply to the drilling tool.

2

Another object of the invention is to make possible a switching over of the fluid or flushing medium supply from one drilling element to the following while drilling is in progress.

Another object of the invention is to make possible efficient and unhindered feeding of the drill string while switching over the fluid supply from one drilling element to the following during progress of the drilling.

A still further object of the invention is to make possible a continuous supply of fluid or flushing medium to the drilling tool through said string during drilling and feeding of the drilling elements of the string one after the other into the ground.

The above and other objects and advantages of the invention will become apparent hereinafter as this description proceeds, reference being made to the accompanying drawings illustrating a preferred embodiment of a device according to the invention.

In the drawings FIG. 1 is a longitudinal sectional view through a portion of a drill string provided with a device according to the invention;

FIG. 2 is a transverse section on line II—II in FIG. 1;

FIG. 3 is a plan view of a coupling device for a supply hose for fluid such as flushing medium;

FIG. 4 is a section on line IV—IV in FIG. 3, and

FIG. 5 is a side view of a portion of a drill string with two coupling devices for fluid in attached position and FIGURE 6 is a side view of the drill bit end of the string in a drill hole.

FIG. 1 shows a portion of a hollow drill string comprising drilling elements 1 and 32 provided with internal threads at 2 and 31 for connection of a threaded connecting element 3, the outer diameter of which is equal to the diameter of the drilling element except for an elongated, substantially cylindrical annular recess 4. In the recess 4 there is located a rotatable swivel bushing 5 having a wall thickness somewhat smaller than the depth of the recess 4 so that the outer diameter of the bushing substantially corresponds to the outer diameter of the drill string. The swivel bushing 5 is provided with a radial aperture 6 therethrough which leads into a peripheral annular groove 7 in the element 3. Between the groove 7 and an axial passage 10 through the element 3 a conduit 8 extends having a one-way valve 12 therein, comprising a ball 13 which is biased against a valve seat 14 in said conduit by a suitable spring 15 disposed in a spring chamber 16. The conduit 8 is connected to the passage 10 by a bore 9.

The passage 10 communicates to the left in FIG. 1 with a passage 11 in the hollow drilling element or drill pipe 1. To the right in FIG. 1 there is arranged a one-way valve 20 in the passage 10, said valve comprising a ball 21, which is biased against a seat 22 by means of a spring 23. The spring 23 is concentrically supported in the element 3 on a suitable shoulder formed by a washer 24 interposed between the parts 3b and 3c of the connection element 3. The one-way valve 20 only permits flow of fluid to the left in FIG. 1 through the element 3.

In order to be able to assemble the bushing 5 in the recess 4 and further for locating the one-way valves 12 and 20, the element 3 is preferably made in two parts 3b and 3c fitted together at 30. These parts may be pressed, screwed or joined together in any other suitable way. To the right in FIG. 1 the element 3 is provided with external threads 31 for screwing on the next drilling element 32, indicated in chain dotted lines in FIG. 1.

The connecting element 3 and the swivel bushing 5 appear also from FIG. 2, which is a cross-section on line II—II in FIG. 1, and in FIG. 5. Externally at both ends the swivel bushing 5 is provided with two peripheral grooves 35, 36, which at points diametrically opposed to

the aperture 6 are provided with small recesses 37 and 38. The grooves 35 and 36 are used as guides in connection with the coupling device for the fluid supply hose, which will be described hereinafter.

FIGS. 3 and 4 illustrate a coupling device for a flushing medium hose, through which flushing medium such as water may be supplied to the passages 10, 11 through the aperture 6 while the drill string is rotating. The coupling device consists of two substantially S-shaped levers 40 and 41, which are pivotally connected to each other by means of a rivet 43. The levers 40 and 41 form a pliers-like device having jaws 44, 45 and shanks 46, 47. The jaws are formed for being connected to the swivel 5 of a connecting element 3 as obvious from FIG. 5. From the face of the jaw 44 project two lugs 50, 51, which are spaced apart and sized to fit into the grooves 35 and 36 of the swivel bushing 5 and to be able to enter the recesses 37, 38.

The jaw 45 has a bore 52, the axis 53 of which points half-way between the lugs 50 and 51. At the face of the jaw 45 is provided a packing gland 54 of rubber or plastic around the bore 52, while the supply hose for the fluid from a suitable fluid source, not shown, is coupled to the outer part of the bore, for example by means of a threaded nipple 56 as indicated in FIG. 4.

The shanks 46, 47 of the levers 40, 41 are provided with a spanner 60, consisting of a left and right hand threaded screw 61 engaging threads in two nuts 70 in the shanks 46, 47, and further provided with a wheel 62 which, when rotated, moves the levers 40, 41 relative to each other.

FIGURE 5 and FIGURE 6 illustrate in three broken apart portions the device according to the invention as applied for continuously supplying flushing water to a rotating drill string during addition of further drilling elements. It is supposed that a leading drilling element 1a carrying a tool such as a diamond bit 69 has penetrated the ground 71 and produced a hole 72. The drilling element 1a is provided at the upper end with a connecting element 3, not shown, which together with the element 1 forms a drill string. The element 1 has at the top a connecting element 3a and attached thereto a coupling device 40a of the types described in connection with FIGS. 1 to 4. Suppose now that during drilling operation a further drilling element 32 and a connecting element 3 is connected to the drill string and that flushing medium has to be admitted therethrough into the drill string projecting above the drilling machine, not illustrated. To this end a further coupling device 40 is attached to the connecting element 3 on top of the added drilling element 32. Such attachment is easy, when the wheel 62 has been turned so that the device 40 may grasp over the element 3 and the lugs 50, 51 enter the guide grooves 35, 36 and ride in said grooves until they engage the recesses 37, 38, in which position the device 40 is fastened to the swivel bushing 5 of the drill string by turning the wheel 62 so that the jaws 44, 45 firmly engage the bushing 5 with the packing gland 54 and opening 52 registering with the aperture 6. Flushing water may now be supplied through the device 40 and the supply through the device 40a may be interrupted by closure of a not illustrated valve in the hose to the device 40a, which may naturally be removed by loosening the spanner screw 61. The above operation may be repeated when further drilling elements 1 and connecting elements 3 are added to the drill string. It would be obvious that flushing water or any fluid supplied under sufficient pressure through the device 40a or 40 will enter the passages 10, 11 through the conduits 3 and flow down the drill string and escape through the flushing water passage 73 in the bit to the drill hole 72 to carry away debris and cool the bit. In order to prevent leakage of flushing medium between the swivel bushing 5 and the element 3 it is preferred to provide packing rings 67, 68, for example made of rubber, as indicated in FIG. 1.

The embodiment of the invention above described and illustrated in the drawings should only be considered as an example and the invention may be modified in several different ways within the scope of the following claims.

5 It should, for instance, be understood that a similar device as described could be used for continuously supplying pressure fluid to a down the hole drill provided at the lower end of a string of drill pipe elements for operating such a drill and for flushing the hole. The device could also be used in connection with more or less conventional percussion drilling with coupled drill steels or drill pipes.

What I claim is:

1. In apparatus of the character described for supplying fluid to a rotating drilling tool at one end of a drill string formed of a number of equivalent detachable hollow drilling elements during rotation thereof from a non-rotating source of fluid, the combination which comprises a connecting element for interconnecting adjoining said hollow drilling elements in said drill string, a longitudinally extending internal passageway in said connecting element for leading said fluid therethrough from one said hollow drilling element to the next and forming with said hollow drilling elements a continuous passage leading throughout said drill string to said tool, means at each 10 opposite end of said connecting element for interconnecting successive hollow drilling elements thereto, first one-way valve means in said passage and permitting flow through said passage in the direction toward said drilling tool but preventing flow in the opposite direction, a conduit leading transversely into said connecting element from the outside thereof to said passage, second one-way valve means for permitting fluid flow through said conduit into said passage but preventing flow in the opposite direction and effective downstream of said first one-way 15 valve means, a swivel bushing rotatably disposed around said connecting element and adjacent said conduit, means for maintaining the axial positioning of said swivel bushing on said connecting element, an inlet opening in said swivel bushing for introduction of fluid flow therethrough, and means providing flow communication from said inlet opening in said bushing to said conduit into said longitudinal passage in substantially all angular positions of said bushing with respect to said connecting element during relative rotation thereof.

2. A connecting element according to claim 1 in which 20 said swivel bushing is disposed in a peripheral annular groove in said connecting element and has substantially no greater maximum diameter than said element.

3. A fluid supply coupling device for engagement with a connecting element as recited in claim 1 and comprising a tong-like member having two jaws adapted for clamping engagement around said swivel bushing, means on one of said jaws for interlocking engagement around the outside of said bushing, passage means through the other 25 of said jaws for engagement in flow communication with said passage in said bushing communicating with said conduit, means for supplying fluid through said passage in said jaw for flow thereof into said connecting element, and means on said tong-like member for maintaining it in clamping and operatively positioned engagement with said swivel bushing.

4. A device for supplying fluid to a drilling tool at one 30 end of a rotary drill string having a source of fluid and comprising a connecting element adapted to form a joint between adjoining drilling elements in a string of a number of equivalent detachable hollow drilling elements, a longitudinally extending internal passage in said connecting element for leading fluid therethrough to said tool, a first oneway valve means located in said passage and permitting flow through said passage in the direction 35 towards said drilling tool but preventing flow in the opposite direction, a conduit leading transversely through said connecting element from the outside thereof to said passage, a second oneway valve means in said conduit 40 permitting flow of pressure fluid from the outside through

said conduit into said passage but preventing flow in the opposite direction, bushing means disposed around said connecting element and rotatable with respect thereto, and coupling means connected to said bushing means for swivelly connecting said source of fluid to said conduit from the outside of said connecting element, and means between said bushing means and said connecting element for providing free flow communication for said fluid between said coupling means and said transverse conduit in said connecting element in substantially all angular positions of said bushing means with respect to said connecting element.

5. A device according to claim 4, in which a peripheral annular recess is located on said connecting member and includes a peripheral annular groove communicating with said conduit, and in which said swivel bushing is rotatably mounted in said recess of said connecting member, and having a passage through the wall of said bushing communicating with said groove, said coupling means being clamped to said bushing and communicating with said bushing passage.

6. Apparatus as recited in claim 5 which also includes means disposed externally on said bushing for receiving said coupling means, means disposed on said coupling means for cooperating with said external means on said bushing, and a fluid opening in said coupling means in flow communication with said passage in said bushing for supplying fluid from said source into said connecting element.

7. In an apparatus of the character described for supplying fluid to a drilling tool at one end of a rotary drill string having a source of fluid and a connecting element for interconnecting adjoining drilling elements in a string of a number of equivalent detachable hollow drilling elements, the combination which comprises a longitudinally extending internal passage in said connecting element for leading fluid therethrough to said tool, a first one-way valve located in said passage and permitting flow through said passage in the direction toward said drilling tool but preventing flow in the opposite direction, a conduit leading through said connecting element from the outside thereof to said passage, a second one-way valve in said conduit permitting flow of fluid from the outside through said conduit into said passage but preventing flow in the opposite direction and effective at a point downstream in said flow from said first one-way valve, a peripheral annular recess on said connecting element, a peripheral annular groove in said recess communicating with said conduit, a swivel bushing rotatably mounted in said recess and including a passage communicating with said groove, a tong-like coupling member having two jaws for grasping around said swivel bushing, a fluid supply passage on one of said jaws opening into a portion of the jaw for engaging said bushing passage, annular guide grooves on the periphery of said swivel bushing, lugs on said other jaw adapted to engage said guide grooves, recesses in said guide grooves, said recesses being engaged by said lugs when said other jaw is in position to provide fluid communication to said bushing passage, and means for holding said coupling member in clamped position on said swivel bushing.

8. In an apparatus of the character described for supplying fluid to a rotating drilling tool at one end of a drill string during rotation thereof from a non-rotating source of fluid, a connecting element for forming a joint between adjoining drilling elements in a string of a number of equivalent detachable hollow drilling elements, said connecting element having a longitudinal passage extending therein with a one-way valve allowing flow to said drilling tool but not in the reverse direction and a conduit extending therein from the outside of said connecting element to said longitudinal passage with a second one-way valve means effective downstream of said aforementioned one-way valve therein for allowing flow to said longitudinal passage but not in the opposite

direction, and a bushing relatively rotatable around said connecting element and having two annular guide grooves in the periphery thereof two recesses in said grooves and an opening communicating with said conduit, the combination which comprises a tong-like coupling device having two jaws for grasping said bushing, a fluid supply passage in one of said jaws opening into a portion of the jaw engaging the periphery of said bushing at the opening therein of said conduit, two lugs on the said other jaw for engaging said guide grooves on the periphery of said bushing and said recesses in said guide grooves when said first jaw is in position to provide flow communication to said transverse conduit in said connecting element, and means for holding said coupling device in engagement on said connecting element.

9. In apparatus of the character described for supplying fluid to a rotating drilling tool at one end of a drill string formed of a number of equivalent detachable hollow drilling elements during rotation thereof from a non-rotating source of fluid, the combination which comprises a connecting element for interconnecting adjoining said drilling elements in said drill string, a longitudinally extending internal passageway in said connecting element for leading said fluid therethrough from one said hollow drilling element to the next and forming with said hollow drilling elements a continuous passage leading throughout said drill string to said tool, a conduit leading through said connecting element from the outside thereof into said internal passage, valve means in said connecting element for selectively permitting fluid flow through said internal passage in the direction toward said tool while preventing flow in the opposite direction and for permitting fluid flow through said conduit from the outside into said passage while preventing fluid flow in the opposite direction, a swivel bushing disposed on said connecting element for rotation with respect thereto, means for holding said swivel bushing against axial displacement with respect to said connecting element upon relative rotation thereof, an inlet passage in said swivel bushing and in flow communication with said conduit in said connecting element in substantially all angular positions of said bushing during said rotation of said bushing with respect to said connecting element, and means for supplying fluid to said inlet passage in said swivel bushing for flow therefrom through said conduit into said internal passage in said connecting element.

10. In apparatus of the character described for supplying fluid to a rotating drilling tool at one end of a drill string formed of a number of equivalent detachable hollow drilling elements during rotation thereof from a non-rotating source of fluid, the combination which comprises a connecting element for interconnecting adjoining said hollow drilling elements in said drill string, a longitudinally extending internal passageway in said connecting element for leading said fluid therethrough from one said hollow drilling element to the next and forming with said hollow drilling elements a continuous passage leading throughout said drill string to said tool, means at each opposite end of said connecting element for interconnecting successive hollow drilling elements thereto, first one-way valve means in said passage and permitting flow through said passage in the direction toward said drilling tool but preventing flow in the opposite direction, a conduit leading transversely into said connecting element from the outside thereof to said passage, second one-way valve means for permitting fluid flow through said conduit into said passage but preventing flow in the opposite direction and effective downstream of said first one-way valve means, a swivel bushing rotatably disposed around said connecting element and adjacent said conduit, means for maintaining the axial positioning of said swivel bushing on said connecting element, an inlet opening in said swivel bushing for introduction of fluid flow therethrough, means providing flow communication from said inlet opening in said

bushing to said conduit into said longitudinal passage in substantially all angular positions of said bushing with respect to said connecting element during relative rotation thereof, a coupling device for engaging said swivel bushing and having a fluid supply passage therein, means on said coupling device and said swivel bushing for said engagement thereof whereby said coupling device holds said swivel bushing against rotation and including means for axially positioning said coupling device with respect to said fluid bushing for direct flow communication

between said fluid supply passage in said coupling device and said fluid inlet opening in said swivel bushing.
